Attorneys.

UNITED STATES PATENT OFFICE

THOMAS N. SOLOMON, OF DETROIT, MICHIGAN

RAPID CUTTING MACHINE

Application filed June 30, 1930. Serial No. 464,899.

This invention relates to a rapid cutting machine.

One of the objects of my invention is the production of a simple and efficient machine which will cut any gauge metal very rapidly by using an air hammer for vibrating the cutting element of my machine.

Another object of my invention is the construction of a simple and efficient cutting machine that can be easily clamped or bolted to a work bench.

A still further object of my invention is the construction of a cutting machine in which the cutting element is of a novel and efficient construction, being cushioned in a practical manner by a spring and adapted to have easily connected thereto an air hammer, for vibrating or oscillating said cutting element.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a view in side elevation of a machine constructed in accordance with the present invention, while

Figure 2 is a front view of the same.

Figure 3 is a vertical longitudinal sectional view of the machine.

Figure 4 is a top plan view.

Figure 5 is a sectional view taken on line 5—5, Fig. 1 and looking in the direction of the arrows.

Figure 6 is a sectional view taken on line 6—6, Fig. 1, and looking in the direction of the arrows.

Figure 7 is a sectional view taken on line 7—7, Fig. 1, and looking in the direction of the arrows.

Referring to the drawings by numerals, 1 designates the base of the machine provided with an upstanding head 2 at one end and at its opposite end with bottom die 3. The base 1 is provided with a plurality of vertical apertures 4 through which may extend suitable bolts for fastening the machine to a bench or like support (not shown).

The head 2 is grooved at 5 in which is slidably mounted the adjustable plate 6. Plate 6 is provided with a screw socket 7 in its inner end, Fig. 3. An integral upstanding flange 8 is formed on head 2 at its outer end, and threaded through this flange is screw 9, carrying a lock nut 10. Screw 9 extends into said socket 7 for adjusting the plate 6 longitudinally upon the head 2. The plate 6 is provided with a large vertical aperture or slot 11 over which is placed a washer 12. Through washer 12 and the aperture 11 extends bolt 13. This bolt 13 is threaded into head 2 so that the adjustable plate 6 can be locked against movement in an adjusted position, for the purpose hereinafter described.

On the outer end of horizontal plate 6 is formed a head 14, in which head is a vertical spring socket 15. This head 14 extends above the upper face of plate 6, and around the head is placed the lower end of channel body 16; this body 16 is substantially U-shape in horizontal cross section, Fig. 7. Rising from body 16 is vertical bracket 17 carrying horizontal bracket 18 in which is positioned air hammer 19.

The lower end of body 16 is secured upon the head 14 by a bolt 20, while the sides 21 of body 16 extend down against the sides of head 14 and plate 6, as shown in Figure 1.

A cutting tool 22 is placed within the channel body 16. This cutting tool is provided at its lower end with a cutting edge 23 and on its upper end with shank 24. The lower cutting edge 23 co-operates with die 3 for cutting or shearing metal; the desired adjustment between cutting edge 23 and die 3 can be obtained to a nicety by the adjustment of screw 9 and the plate 6 upon head 2. The air hammer is mounted upon shank 24, Figs. 1 and 3.

A front guide plate 25 is fastened by bolts 26 to the front edges of the channel body 16, whereby the cutting tool 22 can slide upon the body but will not be accidentally displaced. The front guide plate is provided with an elongated slot 27 in which works the heads of the bolts 28. Upon the inner ends of bolts 28 is fastened a boss or block 29. This block 29 moves synchronously with the cutting tool. A coil spring 30 is seated in

spring socket 15 and bears at its upper end, against the bottom of block 29, so that the tendency is to return the cutting tool to its upper position at all times. In the upper end 5 of channel body 16 is a horizontal bridging web 31, Fig. 3. A cam 32 is placed against web 31 and behind the vertical bracket 17; a bolt 33 extends through the upper end of brace 34, also through the bracket 17 and 10 cam 32 and is threaded into web 31. The lower end of brace 34 is fastened by bolt 35 to the top of the adjustable plate 6. It will, therefore, be seen that the plate 6, channel body 16 and cutting tool 22 are synchronously 15 adjustable upon the base of the machine.

The cam 32 operates upon the block 29 to manually force the cutting tool 22 downwardly when the operator is testing the machine, but when the handle 36 of cam 32 is swung 20 upwardly to the dotted position shown in Fig. 2, the spring 30 will force the cutting tool upwardly so that the work or metal to be operated upon can be placed in position upon the bottom die 3.

25 In operation, with the cam in its normal position as shown by dotted lines in Fig. 2, the air hammer 19 will operate the cutting tool while at the same time, spring 30 will always exert an upward pressure on said tool, 30 which returns it to its upper contacting position with the air hammer; the blow of the air hammer being downward, with the spring 30 for keeping the shank 24 in engagement therewith.

35 While I have described the preferred embodiment of my invention and illustrated the same in the accompanying drawings, certain minor changes or alterations may appear to one skilled in the art to which this invention 40 relates, and I, therefore, reserve the right to make such changes or alterations as shall fairly fall within the scope of the appended claims.

What I claim is:

45 1. In a cutting machine, the combination of a base provided with a die, a body detachably supported upon said base, means fastening said body to said base whereby the body can be adjusted upon said base, a spring re- 50 tracted cutting tool slidably mounted on said body and co-operating with said die, and means for moving said cutting tool.

55 2. In a cutting machine, the combination with a base, of an adjustable plate slidably supported by said base, a body carried by one end of said plate, a cutting tool slidably mounted on said body, a spring engaging a portion of said plate and co-operating with 60 said cutting tool for normally exerting upward pressure thereon, and means for moving said tool downwardly.

65 3. In a cutting machine, the combination of a base provided with an upstanding head at one end, a bottom die on the opposite end of said base, said head provided with a groove

in its top and with an integral upstanding flange at its outer end, a plate slidably mounted in said groove, an adjusting screw extending through said flange and into the inner end of said plate, said plate provided with an enlarged slot over said head, a bolt extending through said slot and into said head, a washer over said slot and on said bolt whereby when the bolt is tightened the plate will be held in an adjusted position upon said head, and cutting means carried by the outer end of said plate and co-operating with said die.

4. In a cutting machine, the combination with a base, of an adjustable plate supported by said base, said plate provided at its outer end with an upstanding head, said head provided with a spring socket, a body fitted upon said head and provided with sides extending down against the sides of the head and plate, a sliding cutting tool mounted in said body, a block secured to said cutting tool, and a spring in said spring socket bearing against said block, and means for actuating said block.

5. In a cutting machine, the combination with a base, of an adjustable plate carried by said base, a channel body supported on said plate, a cutting tool slidably mounted in said channel body, a guide plate against said cutting tool and fastened to the front edge of said channel body, said guide plate provided with an elongated slot, a block against the inner face of said cutting tool, fastening means in said slot of the guide plate and extending through said cutting tool and into said block for securing the block to said cutting tool, said adjustable plate provided with a spring socket under said block, a spring in said socket and bearing at its upper end against the bottom of said block, a cam on said body and engaging said block, and means for actuating said cam.

6. In a cutting machine, the combination with a base, of a plate supported by said base, a channel body resting at its lower end on said plate, a cutting tool slidably mounted in said channel body, a spring engaging said plate, a block on said cutting tool and in engagement with said spring, said channel body provided with an upwardly extending bracket and with a bridging web, a bolt extending through said bracket and into said bridging web, a cam mounted on said bolt and bearing against said spring engaged block on said cutting tool, and means for actuating said cam.

7. In a cutting machine, the combination with a base, of a channel body above said base, means supporting said channel body upon said base, said channel body provided with a bracket and with a bridging web, a cutting tool slidably engaging said bridging web, a horizontal bolt extending through the bracket and into said bridging web, a manu-

ally operated cam on said bolt, and means extending from said cutting tool in engagement with said cam whereby the cutting tool can be manually operated.

5 8. In a cutting machine, the combination with a base, of a channel body substantially U-shaped in horizontal cross section above said base, means adjustably mounting said channel body upon said base, a spring retracted cutting tool mounted in said channel body, cam means for manually operating said cutting tool, and said cutting tool provided with means for attaching an air hammer thereto.

15 9. In a cutting machine, the combination with a base provided with a bottom die, of a body provided with a spring retracted cutting tool, means adjustably mounting said body and cutting tool upon said base, and said cutting tool provided with means for attaching an air hammer thereto.

25 10. In a cutting machine, the combination with a base, of a plate supported upon said base, a detachable body provided with a cutting tool mounted upon the outer end of said plate, means for actuating said tool, and a brace fastened to the upper portion of said body and to said plate.

35 11. In a cutting machine, the combination with a base, of an adjustable plate provided at its outer end with a head, a body fitted upon said head, a spring retracted cutting tool in said body, means for actuating said tool, and a brace secured at its upper end against a portion of said body and at its lower end against the top of said plate.

In testimony whereof I hereunto affix my signature.

THOMAS N. SOLOMON.
